UNITED STATES PATENT OFFICE

ROBERT G. RYAN, OF MINNEAPOLIS, MINNESOTA, ASSIGNOR OF TWO-THIRDS TO
MICHAEL C. THEIS, OF ST. PAUL, MINNESOTA

DISPENSING MECHANISM

Application filed October 19, 1928. Serial No. 313,461.

The present invention relates to a dispensing mechanism and is primarily designed for the dispensing of gelatine capsules containing coloring matter for oleomargarine, although it would be feasible to use the device in planting seeds, for instance, or other purposes where it is desired to eject a predetermined number of articles into a hole made by forcing the device into a substance.

10 In selling oleomargarine, it is customary to furnish free with each package a gelatine capsule containing sufficient coloring matter to color the produce so that the purchaser may, if he desires, color the oleomargarine himself.

An object of the present invention is to make a simple and effective device which may be forced into a substance and eject an article into the aperture formed by this process.

20 In order to attain this object there is provided in accordance with one feature of the invention, a slideable plunger having a pointed, separable shield thereover, the plunger being mounted with a stationary inner tubular member to separate the shield upon the completion of an operation, so that an article contained in the tube may be freed to drop downwardly into an opening made by forcing the pointed shield into a substance. Automatic feed means are provided to feed a pre- 30 determined number of articles into the tubular inner member upon the completion of each operative movement of the device.

These and other features of the invention will be more fully brought out in the following description and the accompanying drawings, wherein:

Figure 1, is a view in side elevation of the device, a portion of a containing member being broken away to disclose the interior construction.

Figure 2, is a view partly in section and partly in elevation, showing the plunger in the act of entering a package of oleomargarine, the gelatine capsule being dropped into the hole thus formed upon retraction of the plunger.

Figure 3, is a sectional view on the line 3—3 of Figure 1, showing a helical feedway with gelatine capsules, therein, one of the capsules being positioned in an opening in an

oscillating disk by which the capsules are successively moved over the discharging tube, Figure 3 showing the device in an unoperated position.

Figure 4, is a view similar to Figure 3, showing the device in an operated position.

Figure 5, is a view in side elevation with part of the container broken away showing the device at the completion of an operative stroke, with a capsule in the act of being discharged into the discharging tube.

Figure 6, is a view in side elevation of the lower portion of the mechanism shown in Figure 5.

Figure 7, is a view of the releasing lock in an open position, and

Figure 8, is a view in side elevation of the container, the lower portion thereof being shown in section to show the construction of the inner portion of the device.

Referring to the drawings in detail, a container A comprises a hollow, cylindrical shell with a bottom member 1 fixedly secured thereto and having a removable cover 2. The cylindrical container A is fastened to a wall as by means of wall brackets 3 and 4. A feed disk 5 is mounted to be rotatable within the lower end of the container A and is provided with a recess 6 therein of a size to receive one

gelatine capsule 7. A shaft 8 is fixedly connected to the disk 5 to rotate therewith and extends through an aperture 9 in the bottom of the container A. A twisted metal strip 10 is fixedly mounted in the lower end of the shaft 8 and rides in a slotted opening in a movable yoke B, the slotted opening being of a size to permit free slideable movement of the strip 10 therein but to prevent rotation of the strip within the slotted opening. The yoke B comprises metal strips 11 and 12 which are fixedly secured to opposite sides of a hollow plunger 13. These strips may be affixed to the plunger as by brazing. Hinged to the upper end of the member 11 is a metal strip 14, being removably locked to the strip 12 as by means of a yoke 15 mounted on a lever 16, said lever being pivotally connected to the upper end of the strip 12. The action of the yoke and lever is believed to be sufficiently familiar to make detailed descrip-

100

tion thereof unnecessary. A stud 17 is mounted in the center of the hinged strip 14 and a coil spring 18 is mounted with the upper end thereof surrounding the stud 17, the lower end of said spring resting upon the top 2 of the container to normally force the yoke B upwardly with respect to the container. The lower end of the plunger 13 is beveled at both sides to bring the sides of the plunger 13 to a point 19 at the lower end. Spring metal strips 20 and 20' are mounted one on each side of the plunger 13 to normally close the lower end of the plunger 13 to provide a pointed wedge-shaped nose over the end of said plunger. Connected to the lower face of the bottom 1 of the container and opening into the interior of the container is a tube 21 upon which the plunger 13 is freely slideable. A helical feedway 22 is provided within the container A extending upwardly approximately one complete revolution above the disk 5, the helical feedway being of a depth to receive one layer of capsules so as to feed them down to the discharge opening in regular succession. An ejector 23 is connected to the upper surface of the disk 5, as best shown in Figure 8, and extends slightly above the upper end of the helical feedway 22 so that upon each operation of the disk 5 the capsules 7 resting above the helical feedway 22 will be ejected sufficiently to prevent two capsules wedging in the opening 6 of the feedway, which might interfere with the spring feeding of the articles to the helical feedway.

The operation of the device is as follows:

The container A is securely connected to the wall by means of brackets 3 and 4 which are screwed to the wall by screws not shown. The device is preferably placed above a shelf, also not shown, the shelf being spaced downwardly from the lower end of the plunger when in a normal position, to permit inserting a carton of oleomargarine beneath the plunger and leave a sufficient distance between the carton and the lower end of the plunger when in the position shown in Figure 5 to permit the ends of the spring metal points to close against the sides of the plunger before the plunger enters the carton of oleomargarine. The yoke latch 16 may then be opened, as shown in Figure 7, and the top 2 of the container may be removed and a quantity of oleomargarine coloring capsules inserted in the container A. Upon placing a carton of oleomargarine beneath the device and forcing it downwardly to the position shown in Figure 2, the plunger penetrates the carton and forces a hole therein. The disk 5 is normally positioned with the opening 6 in the disk in register with the tube 21. Upon an operative movement of the device which is caused by forcing the yoke B downwardly, the disk is moved during the downward stroke of the yoke to the position shown in

Figure 1, in which position one oleomargarine coloring capsule drops into the opening in the disk. This turning movement is, of course, effected by the twisted metal strip 10 lying in the opening in the yoke member 12. Upon the upward stroke of the yoke, the disk is rotated in a reverse direction and, upon the completion of the upward stroke, the opening 6 in the disk is brought into register with the tube 21, the coloring capsule then dropping through the tube and into the opening in the carton of oleomargarine. In a normal position the strips 20 and 20' are held apart by the inner tube 21 which projects downwardly beneath the lower end of the plunger 13, and, since the lower end of the tube 21 is not beveled, as is the lower end of the plunger 13, the plates 20 and 20' are thus forced apart and permit the capsule to drop through.

I claim:

1. A dispensing device, comprising a container having a discharge opening therein, feed means positioned to successively receive articles from said container and feed them into said discharge opening, a slideable plunger mounted beneath said discharge opening, said plunger having an aperture therethrough to permit articles discharged through said discharge opening to pass through said plunger, a shield normally covering the nose of said plunger, means operatively connecting said plunger and said feed means to actuate said feed means upon a slideable movement of said plunger, and means positioned to engage said shield means upon a retractive movement of said plunger to uncover the nose of said plunger to permit an article to drop through said plunger.

2. A dispensing device, comprising a plunger having an aperture therethrough, a shield normally covering the nose of said plunger and means positioned to engage said shield upon a retractive movement of said plunger to uncover the nose of said plunger to permit an article positioned therein to drop through said plunger.

3. A dispensing device, comprising a slideable plunger having an aperture therethrough, feed means positioned to successively feed articles into said plunger, a shield normally covering the nose of said plunger, means operatively connecting said plunger and said feed means to actuate said feed means upon a slideable movement of said plunger, and means positioned to engage said shield means upon a retractive movement of said plunger to uncover the nose of said plunger to permit an article to drop through said plunger.

4. A dispensing device, comprising a container having a discharge opening therein, a helical guide-way in said container terminating adjacent said discharge opening, a slideable plunger mounted beneath said open-

ing, said plunger having an opening therethrough to permit articles discharged through said discharge opening to pass through said plunger, a shield normally covering the nose of said plunger, feed means mounted in said container to successively receive articles from said container and feed them into said discharge opening, means operatively connecting said plunger and said feed means to actuate said feed means upon a slideable movement of said plunger, and means positioned to engage said shield means upon a retractive movement of said plunger to separate said shield means to permit an article to drop through said plunger.

In testimony whereof I affix my signature.

ROBERT G. RYAN.
